UNITED STATES PATENT OFFICE.

JOSEPH M. BARRETT, OF FOSTORIA, OHIO, ASSIGNOR TO THE SWARTWOUT COMPANY,
OF CLEVELAND, OHIO, A CORPORATION OF OHIO.

DESUPERHEATER CONTROL.

Application filed January 3, 1927. Serial No. 158,590.

This invention relates to desuperheating and is particularly concerned with the control of the change in quality of steam by reason of the flow of water to the desuperheater.

It frequently happens in steam power plants that the steam delivered from the boiler or boilers is superheated several hundred degrees. It also happens that it is desired to use only saturated steam or at least steam that is but slightly superheated, for the auxiliary apparatus or for carrying out certain processes where the superheat is disadvantageous or even harmful.

The method of desuperheating steam, shown in the disclosure herewith comprises spraying comparatively cold water under high pressure into a chamber through which the steam passes. The superheated steam picks up the moisture, vaporizes it and delivers substantially saturated steam. The quality or the relative amount of superheat in the steam delivered from the chamber depends upon the rate of flow of water into the chamber.

The design of a given desuperheater establishes certain constant factors but, for the purpose of showing my invention, I presume that the spraying and baffling apparatus in the chamber is such that for steam of a given degree of superheat, if water is trapped at a certain rate immediately below the chamber that substantially saturated steam will be delivered.

It is among the objects of my invention to control the flow of water into the desuperheater so that a certain amount of water will be maintained in a container or receiver disposed below the chamber and in free communication therewith. By so doing, a predetermined amount of water is added to the superheated steam so that saturated steam is delivered. The amount of water then held in the container below the desuperheating chamber is a measure of the quality of the steam delivered. It will be seen that if the inflow of water is stopped, that the superheated steam will pick up all the water with which it comes in contact so that both the desuperheating chamber and the adjacent container or receiver will be quickly dried.

To accomplish the objects of my inven-

tion, I control the flow of water into the desuperheater with relation to the amount of water maintained in the receiver immediately below the chamber and thereby accomplishing the result of delivering substantially saturated steam. As the demand for saturated steam varies, the inflow of superheated steam will vary accordingly, therefore, it is necessary to proportion the inflow of water to the desuperheater so that a certain quality of delivered steam may be maintained. I am able to accomplish this result by controlling the inflow of water into the desuperheater by using as a measure the amount of water in the receiver disposed below the chamber.

If by reason of the primary demand on the boiler, the degree of superheat varies, and I desire to deliver steam of the same quality from the desuperheater, I find that by controlling the inflow of water with relation to the amount of water held in the container below the chamber, that I may compensate for varying degrees of superheat as well as for demand for saturated steam. Thus I am able by very simple installation to accurately and constantly control the input of water so that steam of a certain predetermined quality will always be delivered regardless of the degree of superheat or the demand for saturated steam.

Other objects will become apparent from the following more detailed description of the apparatus employed in my invention, a preferred form of which is shown in the drawings. The essential characteristics are summarized in the claims.

In the drawings Fig. 1 is an elevation of my apparatus including the desuperheater and the receiver; Fig. 2 is an elevation taken substantially at right angles to Fig. 1; Fig. 3 is a detail of the cooler.

In the drawings I show at 1 the desuperheater having the superheated steam inlet at 2 and the saturated steam outlet at 3. At 5 I indicate the water supply pipe leading into the chamber through suitable spraying and baffling means (not shown). In the water inlet at 10, I show a diaphragm pressure actuated valve which controls the flow of water into the desuperheater. This valve is of a type which is normally held closed by the spring 11 and which is forced

to open position as a result of pressure exerted on the diaphragm 12 through the conduit 15 by means presently to be described.

As mentioned above, a container or receiver 40 is disposed immediately below the desuperheater 1 in free communication therewith through the short connection 41, a gauge glass may be used as at 42 to show the water level $L-L$ in the receiver 40. A suitable blow-off valve 43 may be connected to the bottom of the receiver so that an occasional collection of sludge or mud may be blown down.

Disposed to intersect the plane of the water level of the receiver, I show a pressure generator 20, having radiating fins 18 and a filing plug 19. This generator may be of general type shown in the patent to Copley No. 1,193,125 issued August 1, 1916.

The generator is mounted on a conduit which is so connected that the water level in the conduit will be the same as the water level in the receiver. The generator comprises a chamber lying concentric with the conduit and is adapted to contain a volatile and expansible fluid, (called the working fluid) which is put under pressure according to the heat content of the fluid in the conduit adjacent the chamber. This, in turn, is dependent upon the presence of steam or water in that portion of the conduit.

The generator is connected at its lowermost point with the pressure conduit 15 mentioned above which leads to the diaphragm chamber of the valve 10. It will be seen therefore, that when the water level in the receiver rises that the generator will be chilled and the pressure in the conduit 15 and on the diaphragm 12 reduced so that the valve 10 will be forced to a closed position. On the other hand, when the water level in the receiver falls, the steam will move downwardly adjacent the generator thus building up the pressure of the working fluid therein, which will tend to open the valve 10 to permit a greater inflow of water so that a substantially even water level is maintained with the result that the proper amount of water is introduced to the superheated steam so that saturated steam will be delivered.

To effect the operation of the pressure generator, I provide the conduit 21 which I show connected at its upper extremity through the valve 22 to the superheated steam inlet pipe at the point 23. I find it advantageous to connect the conduit 21 either to the superheated steam inlet or the saturated steam outlet rather than any part of the desuperheater or the receiver because of the presence of water or mist in the last named chambers. It is however, possible but not so practical, to connect the upper portion of the conduit 21 to the desuperheater with a suitable trap connec-

tion so that the steam in this portion of the conduit 21 is substantially dry. The conduit 21 leads with suitable connection through the generator 20 through the swingable elbow connections 24, 25 and 26, thence through the valve 27 into a lower portion of the receiver below the water level at the point 30. The portions 31 and 32 of the conduit 21 are disposed to form a drop leg below the point 30, and by reason of the connections 24, 25 and 26, the angular position of the generator may be varied. It will be seen that the rapidity of reaction of the generator is a function of its angular position.

Associated with the portion 32 of the conduit 21, which portion is immediately below the generator, I provide a radiator or cooler 33. This radiator also serves as a cold water reservoir. The cooler may for the sake of convenience, be of a construction similar to the generator proper (see Fig. 3), but the connection with the portion 32 of the conduit is such that water may flow through the whole cooler having an opportunity to pass through the chamber adjacent the heat radiating fins 34 as shown. A plug 32' is put in the conduit; perforations 35 are provided. A suitable blow-down valve 36 is connected to the lowermost portion of the conduit 21 so that the contents of the conduit may be blown out when desired. It is advantageous to position this valve within easy reach of the operator.

The operation of the device is as follows: As soon as superheated steam enters the desuperheater, all of the water contained therein or in the receiver will be picked up. At the same time hot steam will flow in the conduit 21 into the presence of the pressure generator so that a pressure will be exerted which will tend to open the valve 10 and let water flow into the desuperheater. If the valve is forced wide open by reason of high pressure being exerted, a surplus of water will collect in the receiver 40 so that the water level in the receiver will rise until that portion of the conduit 21 within the generator contains water of a low heat content which will tend to chill the generator and throttle the valve 10 so that the inflow of water is balanced against the demand therefor.

Particularly in starting, it is found that the water collecting in the receiver is very hot in that the generator may be very slow to respond to a rapidly rising water level. By the use of the radiator or cooler 33 I am able to chill all of the water which moves upwardly into contact with the generator so that the temperature difference may be sharp and the action of the generator well defined.

The drop leg construction including the portions 31 and 32 of the conduit 21 along with the cooler 33, provides for the mainte-

nance of a reservoir of cold water even in the event that all the water in the receiver is taken up. It will be seen that I gain added advantages by using both the drop leg and 5 cooler.

From the foregoing it will appear that I have provided a simple and rugged control for a desuperheater, that my device can be operated advantageously on high pressure 10 installations and that the wearing and working parts are very few, and that the operation is constant and positive. The quality 15 of the steam delivered may be controlled by reason of the compensation effected both for the degree of superheat and for the demand for saturated steam.

I claim:

1. The method of controlling the flow of water to a desuperheater dependent upon 20 the rate of accumulation of water collected below the desuperheater out of the path of steam but in contact with superheated steam including throttling the flow of water to the desuperheater when the quantity of water 25 collected exceeds a given amount.

2. In combination, a desuperheater, a receiver for water associated therewith, and thermo-responsive means disposed outside of the desuperheater for controlling the flow 30 of water into the desuperheater dependent upon the water level in the receiver.

3. In combination, a desuperheater, a receiver disposed below the desuperheater and in open communication therewith but protected from the flow of steam through the desuperheater and means controlling the flow of water into the desuperheater dependent upon the water level in the receiver.

4. The combination with a desuperheater, 40 a receiver disposed below the desuperheater, means for controlling the flow of water to the desuperheater according to the water level in the said receiver, said means including thermo-responsive means disposed at the water level of the receiver.

5. In combination, a desuperheater having 50 an inlet for superheated steam, an outlet for saturated steam, a water pipe for delivering water to the desuperheater, a valve in said pipe, a receiver positioned below the desuperheater adapted to contain an excess of water delivered to the said desuperheater, and thermo-responsive means responsive to change of water level in the receiver for actuating said valve.

6. In combination, a desuperheater having 60 an inlet for superheated steam, an outlet for saturated steam, a water pipe for delivering water to the desuperheater, a valve in said pipe, means for maintaining an excess of water in the presence of the steam, and thermo-responsive means responsive to change in the amount of said excess water for actuating the valve in said water 65 inlet pipe.

7. In combination, a desuperheater having an inlet for superheated steam, an outlet for saturated steam, a water pipe for delivering water to the desuperheater, a pressure actuated valve in said pipe, a receiver positioned below the desuperheater adapted to contain an excess of water delivered to the said desuperheater, a conduit 70 connected to said receiver and to said steam inlet and pressure generator means associated with said conduit responsive to change of water level in the receiver for varying the opening of said valve.

8. The combination of a desuperheater including a mixing chamber having an inlet for superheated steam and an outlet for saturated steam, a water pipe leading to said desuperheater, a valve in said pipe, means comprising a separate chamber for maintaining below the desuperheater an excess 80 of water in open contact with the steam, and means for varying the opening of said valve dependent upon the amount of said excess.

9. In combination, a desuperheater having an inlet for superheated steam and an outlet for saturated steam, a water inlet pipe connected to the desuperheater, a pressure actuated valve in said pipe, a conduit disposed outside of the desuperheater and connected at its ends to different parts of the desuperheater, and pressure generator means associated with said conduit for controlling the opening of said valve.

10. The combination of a desuperheater having an inlet for superheated steam and an outlet for saturated steam, a water inlet pipe for the desuperheater, a valve in said pipe, a receiver positioned below the desuperheater and in open communication therewith, and adapted to contain an excess of water delivered to the desuperheater, a conduit leading from a point in the receiver below the normal water level thereof, and to the steam inlet, pressure generator means associated with the conduit and positioned in the plane of the normal water level of the receiver, said conduit including a drop leg between the said pressure generator means and the receiver, radiating and cooling means associated with the conduit below said pressure generator, and fluid conducting means connecting the pressure generator with said valve whereby the valve is actuated in response to change in water level in said receiver.

11. The combination of a desuperheater having an inlet for superheated steam and an outlet for saturated steam, a water inlet pipe for the desuperheater, a valve in said pipe, a receiver positioned below the desuperheater and in open communication therewith and adapted to contain an excess of water delivered thereto, a conduit connected to the receiver below the normal water level thereof and to a part of the system containing

dry steam, pressure generator means associated with the conduit and positioned in the plane of the normal water level of the receiver, said conduit including a drop leg 5 between the said pressure generator means and the connection with the receiver, radiating and cooling means added to and associated with the drop leg portion adjacent said generator, and means connecting the pressure generator with said valve whereby the valve is actuated in response to change in water level in said receiver.

12. The combination of a desuperheater having an inlet for superheated steam and 15 an outlet for saturated steam, a water inlet pipe for the desuperheater, a pressure actuated valve in said pipe, a receiver positioned below the desuperheater and in open communication therewith and adapted to contain an excess of water delivered to the de- 20

superheater, a conduit spanning the normal water level of the receiver and connected to the inlet for superheated steam, pressure generator means responsive to change in heat content of the fluid in the conduit for 25 actuating said valve and positioned in the plane of the normal water level of the receiver, said conduit including a drop leg portion below the said pressure generator means, and radiating and cooling means associated with the drop leg, whereby a sharp temperature differential is maintained between the fluid in the conduit above and below the generator so that the valve is quickly responsive to change in water level 30 in the receiver.

In testimony whereof, I hereunto affix my signature.

JOSEPH M. BARRETT.
